FEEDING MECHANISM FOR FOUNTAIN PENS

Max H. Storch, Belle Harbor, N. Y.

Application December 26, 1946, Serial No. 718,483

1 Claim. (Cl. 120—52)

1

This invention relates to a fountain pen and has special reference to the feed member of a fountain pen located between the reservoir or barrel and the pen nib to insure a controlled flow of writing fluid.

This invention relates particularly to a feed bar for conducting writing fluid to the pen nib of a fountain pen comprising an elongated feed member having a plurality of longitudinally extending ink flow channels over a portion of the surface of the feed member.

An object of this invention is to provide a fountain pen having a feed member of the type indicated above in which, under all conditions of use, the flow of ink is controlled and a supply of ink is always available to the pen nib in writing.

Another object of this invention is to provide a fountain pen having an easily removable pen point while preventing leakage of ink between the ink feeding member and the section member.

With the above and other objects in view, the invention will be hereinafter more particularly described, and the combination and arrangement of parts will be shown in the accompanying drawings and pointed out in the claim which forms part of this specification.

Reference will now be had to the drawings, wherein like numerals of reference designate corresponding parts throughout the several views, in which:

Figure 1 is an enlarged longitudinal section view of a fountain pen embodying my invention.

Figure 2 is a view in elevation of the fountain pen shown in Figure 1.

Figure 3 is a top plan view of the ink feeding member.

Figure 4 is a side elevation of the feeding member shown in Figure 3.

Figure 5 is a cross-sectional view, the section being taken as on line 5—5 in Figure 4.

Figure 6 is a bottom plan view of the feeding member.

Figure 7 is a side elevation of the assembled feed mechanism.

Figure 8 is a central cross-sectional view of the assembled feed mechanism shown in Figure 7.

Figure 9 is a cross-sectional view, the section being taken as on line 9—9 in Figure 8.

Figure 10 is a cross-sectional view, similar to Figure 9, with the ink feeding member removed.

In the illustrated embodiment of the invention, the numeral 10 indicates a fountain pen barrel having an external thread 11 for the attachment of a fountain pen cap 12.

A section member 13 is adapted to receive on 55

one end an ink reservoir or rubber sack 14 and has a reduced portion 15 which is designed to fit tightly inside the fountain pen barrel 10.

An annular horizontal seat 17 is provided on the section member 13. The seat 17 contacts one end of the barrel 10 and provides a leak proof joint.

The cap 12 has a hollow inner supplemental cap 18 suitably secured therein. The inner cap 18 has a reduced outer diameter with its external peripheral surface in spaced relation from the inner walls of the cap 12.

The lower end of the inner cap 18 forms a shoulder 19 against which the upper end of the section member 13 abuts and seals the writing nibs 20 of the pen 21 and the ink feed member 22 from the atmosphere.

A clip 24 having an annular head 25 fits on the upper portion of the cap 12. A decorative tip 26 has a threaded portion 27 extending through the annular head 25. The portion 27 engages a threaded aperture 28 in the inner cap 18 whereby the clip 24 is anchored to the pen cap 12.

The section member 13 has a smooth cylindrical bore 30 for receiving the pen 21 and the ink feed member 22 in forced fit relation therein.

This invention provides a snug fitting pen 21 and the easy insertion or withdrawal of the feed member 22 and the pen 21 from the section member 13. The pen 21 is securely retained in position in the bore of the section member.

It is thus possible for the ink to flow only to the channels 33 from the ink sack through the pocket 34, along the uncovered portions 31 of the ink flow channels 33 of the feed member 22 to the nibs 20 of the pen 21. The uncovered portions 31 form an extension ink pocket.

The lower portion of the section member 13 has a bore 31 of smaller diameter than the bore 30 to form a shoulder or sealing seat 32.

The pen 21 is of a length to terminate short of the sealing seat 32. The feed member 22 has longitudinally extending ink flow channels 33 which terminate short of the outer tip of the said member. The channels serve for feeding the ink from the reservoir 14 along the undersurface of the pen 21 to the writing nibs 20 of the pen. A portion of the shoulder 32 is undercut providing a pocket-shaped ink supply pocket 34 to permit controlled ink flow past the shoulder 32 through the ink flow channels 33 to the writing nibs 20. The lower face of the pen 21 bridges the undercut.

As shown in Figure 8, the inner or top wall of the pocket 34 extends to the outer surface of the pen 21 and above the ink flow channels 33.

It is to be noted that the arrangement whereby the concealed end of the pen 21 stops short of the sealing seat 32, that this uncovers a lengthwise portion 37 of the ink flow channels 33 and that a surplus of ink is provided at the inlet to the channels 33 and this causes a controlled free flowing ink supply.

It is also to be noted that while the circular clearances 40 are sealed by the shoulder 32 that the lateral channel extensions or the uncovered end portions 37 of the channels 33 provided by the spaced-apart position of the concealed end of the pen 21 permits free air flow into the pen as the ink is used up.

As best shown in Figure 9, a portion of the circumference of the feed member 22 is cut away to provide a flat surface forming a key 35. A portion of the periphery of the bore 30 has a flat surface 36 in contact with the key 35 and forms a keyway therefor. The key and keyway serve to align the ink flow channels 33 with the pocket 34.

The side portions of the feed member 22 are rabbeted on opposite sides of the ink flow channels 33 to provide pockets 38 which are covered by the pen point 21. The pockets prevent seepage of ink transversely to the direction of the controlled ink flow.

As shown in Figure 9, it will be seen that the pen point 21 extends only partly around the circumference of the bore 30 and that in assembled relation, circular clearances 40 appear between the feed member 22 and the circumference of the bore 30.

It is to be noted that, in practice in the art, the feed member has to be considerably smaller in diameter than the bore of the section member to provide room for the pen point.

The pen point not filling the entire space between the said members, circular clearances are formed which may permit leakage between the feed member and the section member unless sealing means are provided to stop the leakage.

By providing the annular sealing seat in the bore of the section member against which one end of the feed member abuts, this eliminates access of the ink to the said circular clearances.

It is thus possible for the ink to flow only in the controlled channels, namely, from the ink sack through the notch in the sealing seat, along the uncovered portions 37 of the ink flow channels 33 of the feed member to the nibs of the pen point.

In accordance with the patent statutes I have described and illustrated the preferred embodiment.

ments of my invention, but it will be understood that various changes and modifications can be made therein without departing from the spirit of the invention as defined by the appended claim.

5 I claim:

In an ink feeding mechanism for a fountain pen, comprising an elongated ink feeding member having longitudinally extending ink flow channels, a section member having an internal shoulder stop for receiving an end face of said ink feeding member in abutting relation, said shoulder providing a sealing seat extending substantially around the circumference of said feed member for preventing leakage of ink between 10 said members, a portion of said shoulder being undercut, said undercut extending below said shoulder to provide an ink supply pocket communicating with an extension pocket above said ink flow channels, said extension pocket serving 15 to augment the ink flow to said ink flow channels, said members having key and keyway means for aligning said ink flow channels with said undercut, a detachable pen point covering the major portion of said ink feeding member, the lower face 20 of said pen point bridging said undercut and being positioned in spaced-apart relation from said seat to uncover end portions of said ink flow channels and to provide entrance to said channels from a lengthwise portion thereof, the frictionally engaging circumferential surfaces between said pen point and said feed section member being defined by the cross-sectional extent of said pen point thereby providing circular clearances on opposite 25 sides of said pen point whereby a controlled ink flow is provided to said pen point through said ink supply pocket and through said undercut portion of said seat, while said circular clearances permit free air flow into said pen as the ink is used up.

MAX H. STORCH.
